HANG UP RACK FOR KITCHEN TOOLS AND THE LIKE

Leslie W. Seibert, Jr., Northbrook, Ill., assignor to Ekco
Products Company, Chicago, Ill., a corporation of
Illinois

Application September 20, 1957, Serial No. 47,801

Term of patent 14 years

(Cl. D44—29)

Fig. 1 is a top perspective view of a hang up rack for kitchen tools and the like showing my new design.

Fig. 2 is a top plan view thereof.

Fig. 3 is a fragmentary enlarged view showing the details of the pin projecting from the rack.

The characteristic features of the design reside in the dimensional relations whereby the width of the curved indentations and the height of the rack are approximately equal and the depth of the curved indentations is approximately one-half the width thereof.

I claim:

The ornamental design for a hang up rack for kitchen tools and the like, as shown and described.
